INDICATING MEANS FOR ENGINES HAVING THERMOSIPHON OR OTHER COOLING SYSTEMS

Filed Aug. 2, 1918

FIG. 1.

FIG. 2.

FIG. 3

FIG. 4.

Inventor
Harrison H. Boyce
By his Attorney
Edmund George Moses

UNITED STATES PATENT OFFICE.

HARRISON H. BOYCE, OF FOREST HILLS, NEW YORK.

INDICATING MEANS FOR ENGINES HAVING THERMOSIPHON OR OTHER COOLING SYSTEMS.

Application filed August 2, 1918. Serial No. 247,084.

To all whom it may concern:

Be it known that I, HARRISON H. BOYCE, a citizen of the United States, residing at Forest Hills, in the county of Queens and State of New York, have invented certain new and useful Improvements in Indicating Means for Engines Having Thermosiphon or Other Cooling Systems, of which the following is a specification.

10 This invention relates to instruments for indicating the thermal condition of internal combustion engines of automobiles, aeroplanes and the like. Such engines, as is well known, operate satisfactorily only within 15 certain temperature limits, too cool a temperature preventing satisfactory conditions for combustion and possibly resulting in freezing of the cooling water or congealing of the lubricant, and too high a temperature 20 causing overheating. The latter condition is especially undesirable for if continued it will frequently result in serious damage to the engine such as seizing of the pistons, scoring or cracking of the cylinder walls, or 25 other injury. My present invention relates to means forming a guide for the operator of the vehicle enabling him to determine at any time the thermal condition of the engine and also constituting an effective danger signal 30 for warning the operator of the approach of overheating conditions. In the preferred embodiment of the invention illustrated these results are accomplished by the use of an instrument combined with the 35 water circulating cooling system of the engine. As is well known such cooling systems comprise jackets around the engine cylinders and a radiator for cooling the water, connections being provided through which 40 the water is circulated between the jackets and radiator. In many of these cooling systems a pump is utilized for producing a rapid and positive circulation of the water and in such systems, if an adequate radiator is provided, the water will usually be 45 maintained at a temperature considerably below the boiling point. Another very extensively used type of cooling system, however, is that known as the thermo-siphon system in which no pump is employed but in 50 which the water is caused to circulate by the action of gravity owing to the difference in density of the hot water in the jackets and

the cool water in the radiator. In such systems the circulation is usually slow and the water leaving the cylinder jackets and passing to the radiator is very hot, often closely approaching the boiling point. The present invention is especially applicable for use in connection with thermo-siphon cooling systems although it may be employed in other constructions where conditions render it desirable.

When the temperature of the water in the cooling system is normally not far below the boiling point as in the case of thermo-siphon systems it is necessary for the danger indicating signal to be produced by a comparatively slight rise in temperature and the present invention is especially directed to the provision of means capable of acting in this manner. The means which I employ comprise a temperature responsive element arranged to be influenced by the temperature in the cooling system and visual indicating means controlled from the temperature responsive means so constructed as to have a comparatively gradual movement for the changes in temperature in the lower range of the instrument or below a certain point or critical temperature and a more rapid movement at higher temperatures. In the preferred form of my invention I employ a glass tube thermometer type of instrument having an effective cross-sectional bore area which is non-uniform so that for the lower temperatures the rise of the fluid will be gradual, thus permitting an instrument of considerable range to be compressed within small compass, while within the region of the higher temperatures the effective cross-sectional bore of the tubing is reduced whereby a rapid movement of the fluid column is obtained within such range.

In the accompanying drawings which form a part of this specification and in which a preferred embodiment of the invention has been shown as illustrative of the principle thereof:

Figure 1 is a diagrammatic side view of an internal combustion engine of an automobile or other vehicle provided with a cooling system of the thermo-siphon type and showing the invention incorporated therein.

Figure 2 is a view of the face of the indicating instrument shown in Figure 1.

Figure 3 is a vertical section of the thermometer tube, and upper part of the casing.

Figure 4 is a transverse section of the thermometer tube near its upper end.

5 In both Figures 3 and 4 the dimensions of the parts and particularly the diameter of the tube bore, are somewhat exaggerated for clearness in illustration.

Referring to the drawings in detail the 10 numeral 1 designates an internal combustion motor having cylinders 2 surrounded by water jackets 3. These jackets are connected by an outlet pipe 4 with the upper part of a radiator 5, the lower part of which 15 is connected with a return pipe 6 which conveys the water back to the jackets. The cooling water 7, which in the jackets is heated by the heat of the combustion in the cylinders, tends to rise and flows through 20 the pipe 4 into the upper part of the radiator. The water in the radiator which is considerably cooler than the water in the jackets and therefore of greater density descends by gravity and thus a circulation is 25 set up from the jackets to the radiator and then back to the jackets. As this circulation depends entirely upon the slight difference in the density of the water produced by the heating thereof, the temperature of 30 the water is usually high and the water leaving the jackets is frequently but slightly below the boiling point. In many engines this constitutes the normal condition of operation. A slight increase in the temperature in the water, however, so that boiling 35 actually occurs will ordinarily indicate a dangerous or undesirable condition as it tends to show that there is some improper condition of operation and furthermore continued boiling results in the loss of the cooling water and consequently eventually in 40 the failure of the cooling system. The boiling of the water therefore constitutes a condition of potential danger which my invention is designed to render at once noticeable to the operator upon its actual occurrence or even near approach.

In accordance with the preferred form 50 of my invention illustrated I mount in connection with the cooling system and preferably upon the filler cap 8 of the radiator 5 an indicating instrument 9 the construction of which will now be described. As illustrated the instrument comprises a suitable 55 frame secured on the filler cap and carrying a dial plate 10 having a danger zone indicating means preferably in the form of a window 11 in the dial plate. Also mounted in the frame is a glass thermometer tube 12 60 which extends vertically in front of the dial plate and which is provided at its lower end with a bulb 13 of usual construction adapted to extend through an opening in the radiator cap into the radiator. The bulb 65 of the thermometer being influenced by the

temperature of the water coming from the cylinder jackets controls the height of the fluid column 14 and thus causes the thermometer to indicate the thermal condition of the engine and cooling system. In cer-

tain cases, particularly where the cooling system is of the thermo-siphon type, the temperature of the water is normally so

high that the normal reading of the thermometer may be very near the boiling point

75 and as the instrument is usually located on the radiator at some little distance in front of the driver, the slight rise in the column which will occur upon the actual boiling

80 of the water may be difficult of discernment if the ordinary type of thermometer tube is used. It is not feasible to overcome this

85 condition by utilizing a thermometer having a long tube and an even scale throughout as such a thermometer obviously would be undesirable on a vehicle for mechanical

90 reasons. I therefore have produced a tube so constructed as to give a very rapid movement of the column at and near the boiling

95 point. In this way a comparatively short thermometer tube may be employed which

will nevertheless cover the entire range from freezing to boiling and will also yield an extensive and easily observable movement

100 of the liquid column between a point a few degrees below boiling and actual boiling

105 temperature. In the specific construction illustrated I accomplish the desired result by introducing into the upper part of the

110 thermometer tube 12 a filling wire 15 which is sealed at its upper end in the glass and which depends part way down the tube so

115 as to partly fill the bore thereof and thus reduce the volume of the upper part of the

120 bore. The expansion of the liquid in the bulb 13 which is substantially constant for equal changes in temperature will produce a given gradual rate of rise of the column in the tube 12 up to the lower end of the

125 wire 15. Any further increase in the temperature of the bulb will produce a much more rapid rise in the column from that

130 point as the volume of the bore to be filled by the liquid in much less per unit of length.

135 For instance, the tube 12 may have the wire 15 extended downwardly from the top of the tube about one third of the length of the exposed portion of the tube and a distance substantially corresponding with the

140 diameter of the window 11. By selecting tubing and a wire of proper dimensions an instrument may be produced having a scale reading extending from 32° F. or freezing to approximately 200° at the bottom of the wire,

145 the remaining upper range of the scale corresponding to temperatures between 200° and 212°. With this construction comparatively slight changes of temperature in excess of 200° are easily noticeable and movements of the fluid column are produced which

150
